OR D 18,987

DESIGN.

L. H. MARSTON.

ORGAN CASE TOP.

No. 18,987.

Patented Apr. 2, 1889.

UNITED STATES PATENT OFFICE.

LOUIS H. MARSTON, OF CHICAGO, ILLINOIS.

DESIGN FOR AN ORGAN-CASE TOP.

SPECIFICATION forming part of Design No. 18,987, dated April 2, 1889.

Application filed March 1, 1889. Serial No. 301,706. Term of patent 3½ years.

To all whom it may concern:

Be it known that I, LOUIS H. MARSTON, a citizen of the United States, residing at Chicago, county of Cook, and State of Illinois, § have invented and produced a new and original Design for an Organ-Case Top, set forth in the following specification, reference being had to the accompanying engravings, forming a part thereof.

10 This design comprises as separable parts, capable of being employed as independent designs, a design for an ornamental top, being that portion of the total design which is above the entablature B, and the design for a music- 15 desk top, being that portion of the entire design which is included between the principal organ-case entablature A and the ornamental top as above defined. The unitary design for the entire organ-top, comprising both the 20 desk-top and the ornamental top, is distinguished by the following features: At each side of the music-desk there is located an open-fronted alcove, C. The opening in the front of the alcove is made in the form of what 25 is commonly known as a "Moorish arch"—that is, an arch more or less approximately in the form of an arc of a circle, such arc comprising more than one hundred and eighty degrees, so that the base is not the widest part 30 of the arch. Above the music-desk is a large open-front alcove, D, the opening in whose front is also of the form of a Moorish arch. On each side of the alcove D is the alcove E, bounded upwardly by the entablature E, 35 which is continuous across the entire width of the top. Each of the alcoves F has an end opening, F', which is also in the form of a Moorish arch. In the back G of the orna-

mental top, above the entablature E, are a number of openings, H, to lighten the upper 40 part of the ornamental top, all of them being in the same form of a Moorish arch, so that this form of arch characterizes the design throughout.

I claim—

1. The design for an organ-top herein shown and described, comprising an open-fronted alcove at each side of the music-desk, the front openings in said alcove being in the form of a Moorish arch, and comprising a large 50 central open-fronted alcove above the music-desk, the opening in said alcove-front being in the form of a Moorish arch, the back having light-openings H, also in the form of a Moorish arch, substantially as set forth. 55

2. In a design for an organ-case top, the design for a desk-top herein shown and described, comprising an open-fronted alcove on each side of the music-desk, the opening in said alcove-front being in the form of a Moorish 60 arch, substantially as set forth.

3. In a design for an organ-case top, the design for an ornamental top herein shown and described, comprising a large central open-fronted alcove, the opening in said alcove- 65 front being in the form of a Moorish arch, substantially as set forth.

In testimony whereof I have hereunto set my hand, in the presence of two witnesses, at Chicago, Illinois, this 25th day of February, 70 1889.

LOUIS H. MARSTON.

Witnesses:

CHAS. S. BURTON,
JEAN ELLIOTT.
